UNITED STATES PATENT OFFICE.

JOHN WALKER, JR., OF MELROSE PARK, PENNSYLVANIA, ASSIGNOR TO WALKER MANUFACTURING COMPANY, INC., A CORPORATION OF PENNSYLVANIA.

HEDDLE FRAME.

Application filed February 25, 1928. Serial No. 256,831.

The object of the invention is to provide improvements in textile machinery, and more particularly heddle frames for looms.

Another and more specific object is to provide in heddle frames means for stiffening the oppositely positioned rails and for supporting the heddle bars at one or more regions intermediate their end portions where their main support is provided.

10 A further object is to provide an improved stay rod connecting the oppositely positioned rails of the frame to prevent them from springing or flexing out of a predetermined relation with each other, and to efficiently support the usual heddle bars intermediate their ends and prevent their becoming curved or bent, which would permit the bank or series of heddles carried thereby to become shifted at the center out of their common plane.

20 Still another object is to provide a simple yet highly efficient connection between the respective rails of the frame and the ends of the stay rod, whereby the latter effectually resists any tendency of the former to move either toward or away from each other, at the same time permits the ready disengagement of the rod from the frame members.

25 And a still further object is to provide a stay rod of this character with a substantially centrally positioned aperture, opening laterally through one edge and so shaped as to permit the ready insertion of a heddle bar and prevent its accidental removal laterally therefrom, yet permitting the disassociation of said rod and bar in a predetermined manner.

30 With these and other objects in mind, the present invention comprises further details of construction and operation which are fully brought out in the following description when read in conjunction with the accompanying drawings in which Fig. 1 is a front elevation of a heddle frame comprising top and bottom rails and heddle bars connected by a stay or brace embodying and secured in position by features comprising the present invention; Fig. 2 is an enlarged fragmentary portion of the device as shown in Fig. 1 and partly in section; Fig. 3 is a vertical section on the line 3—3 of Fig. 2; and Fig. 4 is a perspective view 35 of the lower end portion of the improved stay rod.

40 Referring to the drawings, a heddle frame is here shown as comprising parallel oppositely positioned top and bottom rails 1 and 2,

55 connected at their ends by any suitable means such as straps 3. Heddle supporting bars 4 and 5 extend longitudinally of the frame parallel with and spaced slightly from the neighboring frame rails 1 and 2, and operatively supporting a bank or series of heddles 6, which are attached thereto in any well-known manner.

60 The stay rod in the present instance is preferably a metal strap which extends transversely in a plane perpendicular to the plane of the rails 1 and 2 and comprises a central portion 7, which adjacent to its opposite ends is bent angularly to provide feet 8, bifurcated by centrally positioned slots 9, which extend longitudinally inwardly from the respective 65 ends of the rod, the terminal portions 10 of each foot being angularly bent in opposite directions so as to be in alignment with each other and therefore substantially parallel 70 with the central portions 7.

75 In their adjacent surfaces the respective rails 1 and 2 are provided with recesses 11, terminating in one direction in shoulders 12 and in the opposite direction in other shoulders 13, between which shoulders are normally positioned the end portions or feet 8 of the stay rod, while adjacent to said last-named shoulders, said recesses are deepened to provide off-sets 14, to receive the toes or 80 terminal portions 10 of said feet.

85 Each of said rails is furthermore provided with a bolt 15, extending therethrough, and in substantial alignment with each other, each bolt having a head 16 adapted to engage the normally outer surface of one of the feet 8, while each bolt is also provided beneath its head with an enlargement 17, which is smaller than the head but larger in cross section than the shank of the bolt, being also of greater extent in one direction than in other, so as to fit snugly within the slot 9 of the foot, to prevent the latter from turning. This bolt also normally secures the foot within the recess 11, the adjacent toes 10 within the deeper off-set 14, and the foot as a whole 90 between the shoulders 12 and 13.

95 It will also be noted that the stay rod adjacent to its end portions is provided with centrally disposed apertures 18, through which the heddle bars are adapted to extend, each of said apertures being guarded by a finger 19 to prevent a bar accidentally escaping therefrom, but opening laterally beyond 100

the free end of said finger to permit the ready removal of the bar through the outlet 20 when desired.

With this construction, the stay rod is normally secured in operative position by the bolts 15 and is prevented from turning by the enlargements 17 within the foot slots 9, and from movement with respect to said rails by the shoulders 12 and 13 in cooperation with the bolts themselves. However, to detach the stay rod from the frame rails, said bolts upon being loosened and moved longitudinally towards each other permit the respectively adjacent foot to be freed from said bolts and from the rails, upon effectively shortening the rod or the distance between its ends by bending or flexing it centrally at the same time permitting relative movement of the heddle bars towards the open ends of the apertures 18, whence they too are freed from engagement with the stay rod.

It will also be noted that the foot termini 10 are tapered by converging the transversely opposite sides thereof, said termini being adapted to be drawn by the attaching means 15 into the body of the frame members 1 and 2, when only the major portions 11 of the recesses are provided for reception of the angularly disposed feet 8. In any such case the toes or termini 10 tend also to contract the slots 9 and thereby bind tighter the enlarged portions 17 of said attaching means 15, and positively prevent even a slight axial oscillation of said rods.

Having thus described my invention, what I claim and desire to protect by Letters Patent of the United States is:—

1. In a heddle frame, the combination of a rail having a recess defined by oppositely positioned shoulders, with a stay rod having a bifurcated angularly directed end portion positioned in said recess between said shoulders, and means engaging said rail and extending through the bifurcated portion of said rod to normally secure said rail and said rod in operative relation, said means when loosened permitting said rod to be separable therefrom by moving said end portion transversely of the adjacent portion of said means.

2. In a heddle frame, the combination of a rail having a recess in turn having an off-set portion, with a stay rod having a bifurcated foot section positioned in said recess and having an angularly bent portion extending into said off-set portion, and fastening means extending through said rail and through the bifurcation of said foot section to prevent the accidental separation of said rail from said rod, said means when loosened

permitting said rod to be released therefrom by longitudinal movement of said foot section transversely of the foot-engaging portion of said means.

3. In a heddle frame, the combination of a rail having a recess in turn having an off-set portion, with a stay rod terminating in an angularly bent foot divided by a slot and positioned in said recess, the portions of said foot upon opposite sides of said slot being angularly bent with respect to said foot and being positioned in said off-set, and fastening means extending through said slot and having a transversely enlarged portion engaging the opposite sides of said slot to prevent said rod and said means from turning axially.

4. In a heddle frame, the combination of a rail having a recess defined by oppositely positioned shoulders and in turn having an off-set portion, with a stay rod terminating in an angularly bent foot divided by a slot and positioned within said recess between said shoulders, the divided terminal portions of said foot being angularly bent with respect to said foot and normally positioned in said recess off-set, and a bolt extending through said rail and having a transversely enlarged portion engaging the opposite sides of said slot to prevent said rod and said foot from turning axially and to prevent said foot from being accidentally withdrawn longitudinally from said recess.

5. In a heddle frame, the combination of a rail having a recess defined by oppositely positioned shoulders, with a stay rod terminating in an angularly bent foot divided by a slot and positioned within said recess between said shoulders, and a bolt extending through said rail and having a transversely enlarged portion engaging the opposite sides of the slot to prevent said rod and said bolt from turning axially and to prevent said foot from being accidentally withdrawn longitudinally from said recess.

6. In a heddle frame, the combination of a rail, with a stay rod comprising a rectilinear body portion extending at an angle to said rail and a foot portion having a slot and positioned parallel with said rail, and fastening means carried by said rail and extending through said slot in said foot to normally secure said foot and said rail together, said foot and said rail being separable by relative longitudinal movement of said foot and transverse movement of the foot-engaging portion of said means.

In testimony whereof I have affixed my signature.

JOHN WALKER, JR.
